POWER FLESHING MACHINES

Le Roy F. Jonas, Wausau, Wis., assignor to Jonas & Sons, Inc., Wausau, Wis., a corporation of Wisconsin

Filed Mar. 10, 1958, Ser. No. 720,341

8 Claims. (Cl. 69—46)

This invention relates to improvements in power fleshing machines, and more particularly to a fleshing machine which is adapted to efficiently remove the flesh from the pelts of mink and other fur bearing animals.

It has heretofore been the general practice in the fur farming industry to flesh the animal pelts by hand, which is a time-consuming and laborious task and which requires a considerable amount of skill. It is therefore a general object of the present invention to provide a power operated fleshing machine which permits the fleshing of a great number of pelts in a relatively short time, and with a minimum of effort and skill.

A particular object of the invention is to provide a fleshing machine wherein a specially shaped, power driven knife cuts the flesh and fat tissue from the pelt, and wherein the pressure of said fleshing knife against the pelt may be readily controlled by the operator of the machine to assure a clean and thorough fleshing job.

A further object of the invention is to provide a power operated fleshing unit which is mounted on a longitudinally movable carriage, the movability of the unit permitting an even and uniform fleshing of the entire length of the pelt.

A further object is to provide a fleshing machine wherein a rotatable, double pelt holding device is employed, thereby enabling the operator of the machine to work on and flesh one pelt while an assistant removes and replaces the other previously fleshed pelt, with a consequent saving in operating time.

A further object is to provide an electrically driven fleshing machine wherein the use of a novel electrical circuit and switch arrangement prevents the overheating of the motor and also substantially reduces the danger of injury to the machine operator.

A still further object is to provide a power fleshing machine which is mounted on an adjustable framework, thereby permitting the adjustment of the machine to suit the height and convenience of the operator.

Further objects of the invention are to provide a fleshing machine which is relatively simple in design and construction, which is exceedingly durable and long lasting, and which is well suited for its intended purposes.

With the above and other objects in view, the invention consists of the power fleshing machine, and all equivalents and modifications thereof, and all of its parts and combinations, as set forth in the following specification and claims.

In the accompanying drawings, in which the same reference characters designate the same parts in all of the views:

Fig. 1 is a perspective view of the improved power fleshing machine;

Fig. 2 is an enlarged fragmentary view showing the motor carriage in front elevation together with the motor and fleshing blade attachment;

Fig. 3 is an enlarged fragmentary sectional view of the motor carriage, together with the motor and fleshing

blade attachment, taken on line 3—3 of Fig. 1, and showing, in broken lines, the lever action of the carriage guide handle;

Fig. 4 is an enlarged rear view of the fleshing blade and slide holder, with a portion of the blade broken away to show the drive rod which actuates the same;

Fig. 5 is an enlarged inverted plan view of the motor carriage;

Fig. 6 is an enlarged top view of the double pelt holding device;

Fig. 7 is an end view of the pelt holding device, taken on line 7—7 of Fig. 6;

Fig. 8 is an opposite end view of the pelt holding device, taken on the line 8—8 of Fig. 6; and

Fig. 9 is an enlarged fragmentary side view of the pelt holder locking mechanism.

Referring first to Fig. 1 of the drawings, it will appear that the fleshing machine comprises in general a rectangular base frame 15 supported by legs 16, and having a pair of horizontal, longitudinal top rails 17. A flat carriage 18 is supported on said rails by wheels 19 which permit the movement of the carriage along said rails. An upright member 20 is mounted on said carriage and supports an encased electric motor 21.

As shown in Figs. 2 and 4, the motor casing 21 has formed thereon a flanged plate 22 which slidably mounts a fleshing blade 23. Said fleshing blade 23 has a short horizontal stroke and is driven by the electric motor 21 through a reciprocating drive shaft 33.

Attached to the rear of the framework 15, and projecting vertically thereabove, are bracketed supporting arms 24 and 25 which are adapted to revolvably carry an elongated spool 26. The spool 26 carries a pair of removable, diametrically opposed poles 27 and 27', on each of which poles a pelt may be mounted for fleshing, as will be more fully described hereinafter.

When the pelts have been properly positioned on the poles 27 and 27', the fleshing blade 23 may be tilted rearwardly to an engaging position with relation to the pelt carried on the forward pole 27, and the fleshing operation commenced.

Referring again to the base frame 15 illustrated in Fig. 1, said frame is preferably formed of steel to provide maximum strength and durability, but other materials may also be used if desired. The legs 16 are independently adjustable, being provided with sliding extensions 16' and screw type clamping means 28, thereby permitting the raising or lowering of the entire assemblage to adapt it to the convenience of the operator. A fat tray 29 is attached to, and supported between, the legs 16, and is designed to catch and retain the severed flesh and drippings from the pelts, to prevent the same from littering the floor. The top rails 17 are L-shaped in cross-section and are bolted or otherwise rigidly connected to the legs 16.

The flat rectangular carriage 18 is supported on the rails 17 by means of wheels, the outermost wheels 19 having peripheral grooves for straddling the vertical leg of the outermost rail 17, and the inner wheels 19' being flanged on one side to insure their proper engagement with the rear rail. It has been found that the employment of grooves in all of the wheels would be unsatisfactory for the reason that said wheels would bind in the event of any unevenness or variation in the space between the rails. The present arrangement, on the other hand, insures the proper positioning of the carriage without danger of binding or of inhibiting the mobility of the carriage.

Single wheels 30 are carried adjacent both the outermost and rear edge of the underside of said carriage, as appears in Fig. 5, and are attached to the carriage by

means of coiled springs 31 and pivotal arms 32. As shown in Fig. 2, said wheels may be moved downwardly and brought into engagement with the underside of said rails 17, where they are held fast against the tension of said springs 31, and whereby they provide clamping means for retaining the carriage firmly on said rails. The rotatable nature of the wheels 30 permits the free movement of the carriage along said rails. To remove the carriage, as for repairs or the like, it is merely necessary to spring said wheels 30 out of their clamping position, and to lift the carriage from the frame.

The carriage 18 includes a marginal portion 41 and a table portion 34, the latter being tiltable on oppositely disposed axial bolts 35. As will best be seen in Figs. 3, 4 and 5, a guide handle 36 projects outwardly from the marginal portion 41 of said carriage and a second, longer guide handle 37 is positioned directly above said first handle. The handle 37 is pivotally mounted on an upright bracket 38 and has its inner end attached to the edge of said tiltable table 34 by means of links 39 and 40. As shown in broken lines in Fig. 3, the downward movement of the free end of said handle 37 raises the outer edge of the table 34 and rotates said table about its pivotal axes 35. Stop bars 42 and 43 are provided on the underside of the table 34 to arrest the tilting movement of said table at a predetermined point.

Referring now to Fig. 5, the underside of the carriage 18 includes an electric switch or circuit breaker designed to permit the turning of the power off and on through the manipulation of the aforementioned guide handle 37. Said switch consists of a plate 44 affixed to the underside of the tiltable table 34, and an adjacent plate 45 on the rigid marginal carriage portion 41, said plates being formed of a non-conducting material. The plate 44 has a metal conducting strip 46 extending forwardly therefrom and plate 45 has a shorter metal conducting strip 47. Normally, the strip 46 extends beneath strip 47 and is spaced a short distance therebelow, as for example one-fourth inch. A cable 48, carrying the electric wires and leading from the source of electricity to the electric motor unit 21, is attached to the underside of said carriage adjacent said switch and has one of its wires 49 connected to both conducting strips 46 and 47. As will be readily appreciated, unless and until there is connection between conductors 46 and 47, a complete circuit is not effected and the machine is idle.

The tilting movement of the table 34, through the downward movement of the handle 37, as hereinabove described, causes contact between the conducting strips 46 and 47, the strip 46 attached to said table moving upwardly to engage the immobile strip 47, and it is through this means that the electric current may be controlled. A second switch 50 (Fig. 3), of the type ordinarily utilized on similar electric motors, is carried on the motor casing 21 and provides a supplemental safeguard, the closing of both switches being necessary to operate the machine.

The particular switch arrangement employed on the underside of the carriage in the present invention has been described herein in considerable detail but it is only by way of example and other arrangements suitable for the described purposes may be substituted. A solenoid switch, for example, might be utilized with equal success and practicability. The feature to be emphasized is that the power may be turned off through the release of the carriage guide handle 37. It has been found that this innovation prevents the overheating of the motor, as the operator frequently releases the handle in order to manually rotate the pelts, or perform some other task requiring the use of his hands. The release of said handle 37 causes the table 34 and attached conducting strip 46 to return to their normal horizontal position, thereby breaking the electric circuit and providing frequent cooling off periods for the motor. This feature is especially important in the fur farming industry where, during the

pelting season, it may be necessary to operate the fleshing machine for many hours at a time.

In addition to substantially increasing the life of the motor, the described electric switch mechanism also reduces the danger of injury to the operator. As indicated above, the dual switch arrangement necessitates both switches being on in order to operate the fleshing blade. Moreover, the switch mechanism carried on the underside of the carriage 18 can only be closed through a positive downward movement of the carriage guide handle 37 and, consequently, the possibility of the blade being inadvertently or accidentally actuated is remote.

Referring now to the upright member 20 which carries the motor unit, the same is rigidly mounted on the top face of the tiltable carriage table 34 and is secured thereto by a bolt 51, projected through a slot 59 in said table, and carries a nut 51', as shown in Fig. 5. The use of a bolt and slot anchoring arrangement permits the sliding adjustment of the upright member 20 with relation to the pelt holding arms 27 and 27' and insures perfect alignment of the same at all times.

The motor unit carried by the upright support member 20 includes a metal casing 21 within which an electric motor is mounted, a blade holder 22, and a fleshing blade 23. Although a wide variety of electric motors can be readily adapted for use in the machine, the conventional jigsaw motor has been found to be especially satisfactory for the reason that its size and reciprocating action are particularly consistent with the design and functional requirements of the present machine.

As illustrated in Fig. 2, the fleshing blade 23 has a concave cutting head, which is designed to conform to the contour of the pelt holding pole 27 which it confronts. The flat body portion of said blade 23 is slidably retained by the flanged plate 22 formed on the motor casing, illustrated in Fig. 4. The cutting head of the blade 23 is concave as described and has the end portions of its legs bent to a generally vertical position. The leading edge of said blade is sharpened to provide the necessary fleshing implement. The drive shaft 33, extending from the motor, is connected to said fleshing blade 23 and drives the same in a short horizontal stroke. The reciprocating blade action thus produced is extremely effective in cutting flesh and fat tissue from animal pelts and is more efficient, as well as many times faster, than the manual fleshing means formerly employed.

In practice, the fleshing blade, and supporting motor unit 21, are tilted rearwardly to a position wherein said blade engages the pelt to be fleshed, the position and mounting of which pelt will be more fully described hereinafter. The tilting movement of said blade is provided through the tiltable carriage table 34 as previously described, and may be regulated by means of the carriage handle 37, which acts as a lever on said table, thereby permitting the operator to apply the cutting pressure necessary for the particular pelt being fleshed. The downward movement of the carriage handle 37 also closes the electric circuit to actuate the fleshing blade, as previously described, thereby accomplishing a dual function.

The pelt holding device generally described above comprises a pair of elongated tapered poles 27 and 27' carried between two end plates 52 and 53, the latter being connected by a bar 54 and supported by a pair of rigid standards 24 and 25 projecting upwardly from the rear 65 of the frame 15. Said poles 27 and 27' are formed of wood or other suitable material, and are provided with extensible leg and tail clamps 55. Each of said poles is designed to wedgingly receive a pelt thereon, the pelts being turned inside out so that the skin is exposed and in position for fleshing.

The poles 27 and 27' are manually revoluble in order that the pelts may be turned by one hand of the operator during the fleshing operation, thereby permitting the fleshing of the entire pelt both circumferentially and longitudinally. The fleshing blade 23 is mounted on the longi-

tudinally movable carriage 18 which makes the latter possible.

The base or enlarged ends of the pelt holding poles 27 and 27' are revolvably carried by the end plate 53 by means of trunnions 67 and 67' projecting from the ends of said poles and adapted to be received in corresponding holes 68 and 68' formed in said end plate. The opposite ends of said poles similarly carry projecting trunnions 57 and 57' which are revolvably retained by plate 52. As shown in Fig. 8, the end plate 52 is provided with slots 59 and 59' into which said trunnions 57 and 57' may be inserted. A pair of catch hooks 60 and 60' are mounted on the outer face of said end plate 52 adjacent said slots. Said hooks 60 and 60' are forcefully maintained in their hooking position by means of spring arms 69 and 69' and are adapted to engage the projecting ends of the trunnions to retain said trunnions in their inserted positions. When it is desired to remove the poles, or either of them, as when a finished pelt is to be removed and replaced on one of the poles, it is merely necessary to force the spring catch hook 60 or 60' out of engagement with its trunnion and to lift the pole from between the end plates.

The general practice with respect to the operation of the improved fleshing machine is to have an assistant place a new, unfleshed pelt on the rear pole 27' while the operator removes the flesh from the pelt carried by the forward pole 27. When the operator finishes said pelt he may instantly rotate the pole-holding unit 180 degrees on its pinion axes, thereby moving the rear pole 27', containing the new, unfleshed pelt, to the forward position where it is in position for fleshing, while the pole 27, containing the finished pelt, is swung to the rear where the assistant may remove and replace said finished pelt. As a result of this revolvable double pelt holding arrangement, there is a minimal loss of operating time while the pelts are being positioned for fleshing and, consequently, the operator of the machine can flesh a considerably greater number of pelts than was formerly possible.

As will best be seen in Fig. 9, a horizontal locking pin 61 is slidably carried on the underside of the inverted L-shaped supporting arm 25 adjacent the end plate 52. Said plate 52 has a pair of diametrically opposed openings 62 and 62' (Fig. 8) therein, either of which may receive and engage said pin 61 to lock the plate and attached pelt holding poles against inadvertent rotation. Said openings are so aligned in the end plate 52 that said plate may be locked with either pole 27 or 27' in forward, or operating position with relation to the fleshing blade 23. A coiled spring 70 is carried within a casing 63 surrounding the pin 61 and causes said pin to normally assume its projected or locking position. In order to retract the pin, as when it is desired to rotate the pelt-holding poles for the removal and replacement of a finished pelt, the pin may be pulled out of its retaining hole 62 or 62' by means of a lever 64 pivotally connected to said pin and projecting upwardly from said support arm 25, the aforementioned spring returning said pin to its locking position upon the release of said lever. As will be readily appreciated, this retractable locking pin device serves to secure the pelt holding poles in operative position, and permits the exertion of considerable cutting pressure against the pelt being fleshed, thereby enhancing the efficiency and effectiveness of the fleshing action.

Various changes and modifications may be made without departing from the spirit of the invention as above described, and all of such changes are contemplated as may come within the scope of the claims.

What is claimed as the invention is:

1. In an animal pelt fleshing machine including a base; an elongated pelt mounting member; a carriage mounted on the base for movement longitudinal of the axis of the pelt mounting member, said carriage having a pivotally

mounted table portion tiltable in a plane transverse to the axis of the pelt mounting member; an electric motor mounted on the tiltable table portion of the carriage and having a drive shaft; and a fleshing blade carried by said shaft to operatively engage and longitudinally traverse a pelt on said mounting member upon the longitudinal movement of said carriage on the base, the pressure contact of the fleshing blade relative to a pelt on the mounting member being regulatable by a tilting movement of the carriage table.

2. In an animal pelt fleshing machine including a base; an elongated pelt mounting member carried by the base; a carriage mounted on the base for movement longitudinal of the axis of the pelt mounting member, said carriage having a pivotally mounted table portion tiltable in a plane transverse to the axis of the pelt mounting member; an electric motor mounted on the tiltable table portion of said carriage and having a reciprocal motion transmitting shaft; an electric circuit including the motor; a fleshing blade carried by the motor shaft to operatively engage and longitudinally traverse a pelt on said mounting member upon a longitudinal movement of said carriage on the base when the table portion of the carriage is tilted toward the pelt mounting member, the pressure contact of the fleshing blade relative to a pelt on the mounting member being regulatable by the tilting movement of the carriage table portion; and a circuit breaker in said electric circuit associated with said carriage and operated by the tilting movement of said carriage table portion, the tilting of said carriage table portion toward the pelt mounting member closing the circuit to operate the motor and knife, and the return of said table portion to its normal position opening the circuit.

3. A machine for fleshing animal pelts comprising: a base; an electric motor mounted on said base; a movable fleshing blade attached to and driven by said motor; a pair of spaced support arms attached to said base; a pair of end plates revolvably carried by said support arms; and a plurality of pelt mounting poles interposed between and revolvably and removably carried by said end plates adjacent the fleshing blade.

4. In an animal pelt fleshing machine including a base; an electric motor longitudinally movably mounted on said base and having a reciprocal motion transmitting shaft; a plurality of pelt-holding poles individually and jointly revolvably mounted adjacent said motor; and a fleshing blade carried by the motor shaft to operatively engage and longitudinally traverse pelts mounted on one of said poles upon longitudinal movement of said motor on said base.

5. A machine for fleshing animal pelts comprising: a base; a prime mover mounted on said base and having a motion transmitting member; a fleshing blade carried by said motion transmitting member; a movable multiple pelt holding spool; and means for locking said spool in a selected position.

6. In an apparatus for fleshing animal pelts: a base; spaced supports thereon; a pair of pelt holding poles interposed between and removably jointly movably carried by said spaced supports; a tiltable table carried by said base; an electric motor mounted on said tiltable table; a pelt fleshing tool associated with and driven by said motor, said tiltable table being tiltable in a plane transverse to the longitudinal axis of said pelt holding poles to permit the operative engagement of said tool with a pelt mounted on one of said poles; an electric circuit including said motor; and a circuit controller in said circuit and operatively associated with said tiltable table, whereby when said tiltable table is tilted in one direction the circuit will be broken.

7. A machine for fleshing animal pelts comprising: a base; an electric motor mounted on said base; a movable fleshing blade attached to and driven by said motor; a pair of spaced support arms attached to said base; a pair

of end plates revolvably carried by said support arms; and a plurality of pelt-mounting poles interposed between and revolvably carried by said end plates adjacent the fleshing blade, one end of each of said poles being removable from its end plate mounting.

8. A machine for fleshing animal pelts comprising: a prime mover having a motion transmitting member; movable fleshing means operatively connected to and driven

by said motion transmitting member; and a plurality of individually and jointly revolvble pelt-holding poles mounted adjacent said fleshing means.
